DESIGN FOR A REFRESHMENT STAND

Louis F. Mueller, Buffalo, N. Y.

Application October 14, 1938, Serial No. 80,449

Term of patent 3½ years

To all whom it may concern:

Be it known that I, Louis F. Mueller, a citizen of the United States, residing at Buffalo, in the county of Erie and State of New York, have invented a new, original, and ornamental Design for Refreshment Stands, of which the following is a specification, reference being had to the accompanying drawing, forming a part thereof.

I claim:

The ornamental design for a refreshment stand, substantially as shown.

LOUIS F. MUELLER.
